UNITED STATES PATENT OFFICE.

EARL B. NEWMAN, OF FINDLAY, OHIO.

LIGHTING-FIXTURE.

1,396,654.

Specification of Letters Patent. Patented Nov. 8, 1921.

Application filed November 6, 1919, Serial No. 336,126. Renewed September 14, 1921. Serial No. 500,705.

To all whom it may concern:

Be it known that I, EARL B. NEWMAN, a citizen of the United States, residing at Findlay, in the county of Hancock and State 5 of Ohio, have invented certain new and useful Improvements in a Lighting-Fixture, of which the following is a specification.

This invention relates to improvements in lighting fixtures primarily designed for interior lighting and has for its object to provide a device of this character in which substantially all portions thereof which are exposed to view are constructed of wood whereby the character and finish of the wood may 10 be varied according to the wood work or furniture of the room or apartment wherein the fixture is located to increase the esthetic value of the general appearance of the room by securing harmony of color, finish and 15 design of the fixtures and furnishings.

Another object is the provision of a fixture of this character wherein the combustible wood is effectively protected against the action of fire and heat in a short circuit of the 20 electrical conductors extending therethrough or from other causes by the provision of adequate fire-proofing material to the portions of the wood which are exposed to the electrical conductors.

With these and other objects in view as will appear as the description proceeds, the invention comprises the features of construction, combination and arrangement of parts as will be clearly apparent from the 35 following specification taken in connection with the accompanying drawings in which:—

Figure 1 represents a side elevation of the improved fixture.

Fig. 2 represents a fragmentary enlarged 40 sectional view through the supporting base.

Fig. 2^a is a sectional view of the eye bolt and spacing element.

Fig. 3 represents a longitudinal sectional 45 view through a modification of the invention.

Referring to the drawing in detail, wherein similar reference numerals designate corresponding parts throughout the several 50 views, the numeral 5 indicates a supporting canopy which is constructed of wood and, in the spirit of the invention, it is evident that the character of the wood and general design of the canopy may be widely varied 55 to secure harmony between visible details comparatively between the fixture of wood-

work or furnishings of the room. The canopy 5 is adapted to be supported from the ceiling of a room or other apartment and is provided in its upper portion with a cavity 60 6 receiving a correspondingly shaped lining 7 of metal or other fire-proof material which is preferably flanged as indicated at 8 to maintain it in position. The canopy 5 is formed with a plurality of diverging openings 9, the number of which may vary as necessity or preference may dictate and the wood casings or coverings 10 for the fire-proof tubes or conduits 11 are fitted terminally in the apertures 9 and are preferably 65 anchored at their extremities whereby the casings may be securely wedged in position and thereby firmly held in place. The tubes or conduits 11 are preferably constructed of metal or other rigid fire-proof material and 70 are provided with threaded open upper extremities receiving nuts 12 which are arranged within the cup-like lining 6 and limit the downward longitudinal thrust of the tubes. 75

The lower extremities of the conduits 11 below the extremities of the casings 10 are provided with integral or attached depending eyes 13 which are linked in the circular apertured upper extremities 14 of eye 80 bolts 15 positioned transversely through and adjacent the outer edge of an ornamental supporting and spacing element 16.

The lower extremities of the eye bolts 15 are provided with apertured heads 17 receiving the supporting members 18 of preferred types of incandescent lamp sockets 18 adapted to receive preferred types of lamps (not shown) for illuminating purposes. 95

The canopy 5, conduit casings 10 and combined supporting and spacing elements 16 are constructed of wood, the character, design and finish of which may be readily varied, as will be understood, to properly harmonize with the woodwork or furnishings of the room or other apartment in which the fixture is located and the conductors whereby an electrical current is supplied to the lamps mounted in the sockets 18 are 100 positioned through the conduits 11 and through longitudinal openings formed in the eye bolts 15, thereby obviating danger of injury to the woodwork or furnishings due to excessive heating of the electrical 110 conductors.

Referring to the modification of the inven-

tion illustrated in Fig. 3, the canopy 20 is designed for attachment to a vertical wall to provide a "side wall fixture," and the canopy is constructed of wood and provided 5 in this instance, with an integral horizontal extension 21 constituting a casing or covering for the conduit 22 which is arranged longitudinally therein. The canopy 20 is provided with a cavity for the reception of 10 the electrical conductors in which is arranged a metallic fire-proof lining 23. One extremity of the conduit 22 is externally threaded and receives a nut 24 whereby it is maintained in position and the opposite extremity of the conduit is connected with an 15 elbow 25 extending through the lower portion of the extremity of the casing or covering 21 and connected with an incandescent lamp socket 26 adapted to receive a preferred 20 type of incandescent lamp (not shown).

What I claim is:

In a lighting fixture of the class described

comprising a wooden, hollow, substantially semi-spherical canopy, a fire proof metallic lining for said canopy, said canopy being 25 provided with a plurality of diverging openings therein, wooden casings having fire proof metallic conduits therein fitted terminally in the diverging openings, and threaded to receive securing nuts thereon 30 arranged within the hollow canopy, depending eyes carried by the lower extremities of said metallic conduits, an enlarged spacing element provided with a plurality of vertical apertures therein near its outer periphery, 35 eye bolts positioned within the said vertical apertures and connected to the depending eyes, and loosely connected depending sockets carried by the lower terminals of the said eye bolts and beneath the spacing ele- 40 ment.

In testimony whereof I affix my signature hereto.

EARL B. NEWMAN.
